Primary Examiner — Sandra S Snapp(74) *Attorney, Agent, or Firm* — Dinsmore & Shohl LLP**(57) CLAIM**

The ornamental design for a watch case, as shown and described.

DESCRIPTION

FIG. 1 is a perspective view including a rear, top and one side of the watch case;

FIG. 2 is a perspective view including a front, top and one side of the watch case, wherein a watch is shown within the case in broken lines;

FIG. 3 is a side elevation view of the watch case of FIG. 1; FIG. 4 is an opposite side elevation view of the watch case of FIG. 1;

FIG. 5 is a front elevation view of the watch case of FIG. 1; FIG. 6 is a rear elevation view of the watch case of FIG. 1; FIG. 7 is a top plan view of the watch case of FIG. 2; FIG. 8 is a bottom plan view of the watch case of FIG. 1; and,

FIG. 9 is an exploded perspective view of the front, a top, and a side of the watch case of FIG. 1.

The broken lines shown in the drawings depict portions of a watch and form no part of the claimed design.
